UNITED STATES PATENT OFFICE.

PRESTON W. CUMMINGS, OF ROCKFORD, ILLINOIS, ASSIGNOR TO BARBER-COLMAN COMPANY, OF ROCKFORD, ILLINOIS, A CORPORATION OF ILLINOIS.

HEDDLE-HANDLING MECHANISM.

Application filed June 15, 1925, Serial No. 37,176. Renewed September 6, 1928.

This invention relates to means for operating upon independent or detached metallic heddles, such as wire, steel and swaged heddles, and especially steel heddles of the general type disclosed in the Fehr Patent No. 673,499 and the Kaufmann Patent No. 1,090,858. The invention has special reference to means for selecting heddles singly and advancing them into or toward a position where some operation may be performed upon the heddles, as, for example, the drawing-in of warp threads.

More particularly, the object of the invention is to provide a heddle selecting and advancing mechanism which shall be very simple in construction and the movements of which shall be of a very simple character.

In the accompanying drawings, Figure 1 is a fragmental elevation of a machine embodying the features of my invention.

Fig. 2 is a horizontal sectional view taken in the plane of line 2—2 of Fig. 1.

Figs. 3 and 4 are sectional views taken approximately in the plane of line 3 of Fig. 1.

Figs. 5 and 6 are fragmental perspective views showing different positions of the heddle selecting and advancing device.

Fig. 7 is a detail view of the heddle selecting and advancing device.

Figs. 8, 9, 10 and 11 are fragmental perspective views showing various positions of the heddle selecting and advancing device.

Fig. 12 is a section on line 12—12 of Fig. 2.

The invention claimed hereinafter is especially intended for incorporation in a machine for operating upon heddles, as, for example, a warp-drawing machine, but the mechanism shown in the drawings is merely illustrative of the invention and does not represent the invention in operative relation to the other mechanisms of a complete machine.

The invention is especially, although not exclusively, intended to select and position heddles while the latter are contained in an ordinary heddle frame. Herein there is shown a rigid heddle frame of the general

type shown in the Kaufmann Patent No. 1,168,308, said frame comprising a top bar 1, an end bar 2, and a top heddle-supporting bar 3.

While the invention may be employed in connection with heddles of various forms, the mechanism shown in the drawings is especially intended to operate upon heddles A consisting of a thin narrow strip of steel having at each end an elongated opening B by means of which the heddles may be strung or slidably mounted upon the upper heddle-supporting bar 3 and a similar bottom bar (not herein shown). Just below the upper opening B the heddle is provided with an offset portion having a flat surface D (Fig. 6). When the heddles are placed in alternating arrangement with the surfaces D in contact there is formed a series of spaces E in the horizontal plane of the offsets and a series of spaces F below the series of offsets. As shown in Fig. 6, there is a space E at one side of each heddle and a space F at the opposite side of the heddle.

Any suitable means may be employed to support the heddle frame. The specific character of the heddle-frame supporting means will depend in part upon whether the heddle frame be traversed past stationary heddle-handling mechanism or whether the heddle frame is stationary and is traversed by the heddle-handling mechanism. While the invention comprehends both arrangements, the present drawings illustrate a stationary mechanism past which the heddles are arranged to move.

Referring now to Figs. 3 and 5: 4 and 5 are guide plates fixed in the framework of the machine and extending horizontally a short distance below the series of offsets D. The space between the guide plates 4 and 5 constitutes a guideway 6 through which the heddles may travel. Any suitable means may be employed to keep a group of heddles compacted together in the guideway 6 with the leading heddle pressed against the selecting mechanism. Herein I have shown a slide 7 (Fig. 2) mounted in a guideway 8

(Figs. 1, 2 and 3) provided in the framework of the machine, said guideway extending parallel with the guideway 6. To the slide 7 is pivoted at 9 (Fig. 2) a presser finger 10 arranged to bear against a heddle at or adjacent to the offset D. The operative position of the presser finger is determined by contact of the stop portion 11 of said finger with the slide 7. Any preferred means may be used to urge the slide 7 in the direction to press the finger 10 against the heddles. Herein is shown a weight 12 (Fig. 2) which is connected to the slide 7 by means of a flexible connection 13, said connection extending over a guide sheave 14.

In the present instance, each space E and F is as deep as the width of an individual heddle. In other words, the spaces extend entirely through the series of heddles. Each 20 of said spaces provides an entrance for a relatively thin selecting device, which is followed by a wedging device that serves positively to push apart the two heddles between which the given space is formed.

In the present embodiment of the invention the heddle-selecting and positioning mechanism comprises a device S (Fig. 7) which rotates through one revolution to select and advance a heddle and then rotates 30 in the opposite direction through the same distance to select and advance the next succeeding heddle. Said device comprises an approximately triangular plate 15 (Fig. 7) which serves as an abutment or stop for the unselected heddles. The selecting and advancing device S further comprises a plate 16 spaced away from the abutment plate 15 sufficiently to accommodate a single heddle (see Fig. 12). The plates 15 and 16 are 35 rigidly secured together. The plate 16 is approximately rectangular. The corners indicated at 17 and 18 are the portions which pick off, select or initiate the separation of the foremost heddle from the next adjacent heddle. The selector 17 selects a heddle 40 when the selecting and advancing device S turns in one direction, and the selector 18 selects the next heddle when the device S turns in the opposite direction. As shown in 45 Fig. 12, the edges of the plate 16 are sharpened or reduced in thickness to facilitate the entrance of the corners 17 and 18 between two heddles.

The selecting and advancing device S 50 further comprises a wedge-shaped projection 19 on the plate 16, said projection extending away from the unselected heddles, and being diametrically opposite the abutment 15 and the pair of selectors 17 and 18. As shown in Fig. 12, both sides of the projection 19 are inclined at the same angle, one side serving to advance a heddle previously selected by the corner 17, and the other side 55 acting to advance a heddle previously selected by the corner 18. Inasmuch as the

wedge 19 is capable of advancing a heddle when swung in either direction it may be termed double-acting.

As shown in Figs. 5 and 7, that portion of the plate 15 which acts as an abutment for the unselected heddles extends farther from the axis of the selecting and advancing device S than do the selecting corners 17 and 18, and is located between said corners.

While the heddle-selecting and advancing 75 device S has been described in considerable detail, it will be understood that it is susceptible of modification in shape, proportions, and other respects.

The selecting and advancing device may be 80 mounted in the machine frame in any preferred manner. Herein it is shown as secured to a shaft 20 (Fig. 12) which is mounted in bearings 21, the axis of said shaft being approximately in the horizontal 85 plane of the lower ends of the offset portions D.

The selecting and advancing device may be driven by any desired means, that herein shown being purely illustrative. As herein shown, a pinion 22 is fixed upon the shaft 20 and meshes with rack teeth 23 formed on a bar 24 (Fig. 3) which is guided in the machine framework for rectilinear reciprocation. On the bar 24 is a yoke 25 which is engaged by a roller stud 26 on a crank arm 27 fixed upon a shaft 28.

In order to insure that the foremost heddles are down in proper position for selection by the heddle-selecting and advancing device S, I provide means which, while it may be of any desired character, is herein shown as consisting of a presser foot 29 attached to a sleeve 30 which is slidably mounted upon the bar 24. A pin 31 carried by said bar is arranged to lift the sleeve 30 in the upward movement of the bar 24 so as to raise the presser foot 29, as shown in Fig. 3. In the downward movement of the bar 24, the descent of the presser foot 29 is limited by contact of the sleeve 30 with a stationary stop 32, the presser foot not being permitted to bear against the series of heddles. In its downward movement, the presser foot 29 is yieldingly pressed against any heddle that may be slightly above its normal position by means of a coiled spring 33 surrounding the bar 24 between the sleeve 30 and a collar 34 fixed on said bar.

As hereinbefore stated, the device S makes a complete revolution in each cycle. Fig. 8 illustrates the device S in its initial or at-rest position, the arrow indicating the direction in which the device is about to turn. The operation is as follows:

Assuming the parts to be in the position shown in Fig. 8, it will be seen that as the heddle-selecting and advancing device S turns in the direction indicated by the arrow in Fig. 8 and the parts assume the po-

sition shown in Fig. 9 with the foremost unselected heddle in contact with the plate 15, the group of unselected heddles is pressed against said plate by means of the presser foot 10 (Fig. 2). As the turning movement continues, the selecting portion 17 enters the space F between the first two unselected heddles, the plate 16 is inserted between the foremost unselected heddle and the next succeeding heddle (as shown in Fig. 10), the plate 15 revolves clear of the foremost unselected heddle and the wedge-shaped projection 19 enters the space F between the first two unselected heddles, said projection 19 serving to push the heddle along the bar 3 as shown in Fig. 11. It should be noted that the heddle-selecting and advancing device S has completed one revolution when it assumes the position shown in Fig. 11. It then begins to rotate in the opposite direction as indicated by the arrow in Fig. 11. During the rotation in the opposite direction the parts assume the position shown in Fig. 5 wherein the group of heddles, (it is to be noted that there are no selected heddles shown in Figs. 5 and 6) is pressed against the plate 15 by the presser foot 10. As the heddle-selecting and advancing device continues to rotate, the selecting portion 18 enters the space E between the foremost and the next succeeding heddle and as the turning movement continues the plate 16 is inserted between the said first two heddles as shown in Fig. 6. Upon further rotation the plate 15 is swung clear of the foremost heddle and the wedge-shaped projection 19 enters the space E between said heddle and the next succeeding heddle, said projection operating to advance the heddle selected by the portion 18 along the bar 3 as shown in Fig. 8. With the device returned to this normal rest position one cycle is completed and the parts are in readiness to rotate in the direction indicated by the arrow in Fig. 8 to commence the selection of the next heddle.

It will be seen that the heddle selecting and advancing mechanism herein disclosed is very simple in construction, and may be actuated by a very simple drive, since its motion consists merely of rotation first in one direction and then in the opposite direction. The heddle selecting and advancing device S is adapted to pick up and advance the heddles successively with certainty. While the present embodiment of the heddle-selecting and advancing mechanism has been described in considerable detail, it should be understood that the invention is not limited to such details, but, on the contrary, may be modified in various respects without departing from the spirit of the invention as set forth in the appended claims.

I claim as my invention:

65 1. A heddle-selecting mechanism to operate upon a group of steel heddles, each

having an offset near its upper end, the heddles alternating in position with the outer sides of the offsets in contact so as to form a series of spaces E in the horizontal plane 70 of the offsets and a series of spaces F below the series of offsets, said mechanism comprising a heddle-selecting and advancing device mounted for rotation upon an axis parallel with and adjacent to the horizontal 75 plane of the lower ends of said offsets, said device comprising an abutment plate, a selecting plate spaced from the abutment plate sufficiently to receive a single heddle, said selecting plate having a portion adapted to 80 enter a space E when such a space is in the vertical plane of the selecting plate, and another portion adapted to enter a space F, when such a space is in the vertical plane of the selecting plate, said abutment plate extending farther from the axis of said device than do said selecting portions and being located between said selecting portions, and a wedge-shaped projection on the selecting plate on the side of the axis of said device 90 opposite to said selecting portions, means to rotate said device alternately in opposite directions through one revolution, and means to press a group of heddles against said device whereby to bring spaces E and F alternately into the vertical plane of the selecting plate. 95

2. A heddle-selecting mechanism to operate upon a group of steel heddles, each having an offset near its upper end, the heddles alternating in position with the outer sides of the offsets in contact so as to form a series of spaces E in the horizontal plane 100 of the offsets and a series of spaces F below the series of offsets, said mechanism comprising a heddle-selecting device mounted for turning movement upon an axis parallel with and adjacent to the horizontal plane of the lower ends of said offsets, said device comprising an abutment plate, a selecting 105 plate spaced from the abutment plate sufficiently to receive a single heddle, said selecting plate having a portion adapted to enter a space E when such a space is in the vertical plane of the selecting plate and another portion adapted to enter a space F, when such a space is in the vertical plane of the selecting plate, said abutment plate extending farther from the axis of said device than do said selecting portions and being 110 located between said selecting portions, means to turn said device alternately in opposite directions and means to cause relative approaching movement of the group of heddles and the selecting device, whereby to 115 bring spaces E and F alternately into the vertical plane of the selecting plate. 120

3. A heddle-selecting mechanism to operate upon a group of steel heddles, each having an offset near its upper end, the 130

heddles alternating in position with the outer sides of the offsets in contact so as to form a series of spaces E in the horizontal plane of the offsets and a series of spaces F below the series of offsets, said mechanism comprising a heddle-selecting device mounted for rotation upon an axis parallel with and adjacent to the horizontal plane of the lower ends of said offsets, said device comprising an abutment, two selectors spaced from the abutment sufficiently to receive a single heddle and located at opposite sides of the abutment, one of said selectors being adapted to enter a space E when such a space is in register with said selector, and the other being adapted to enter a space F, when such a space is in register with the last mentioned selector, means to turn said device alternately in opposite directions and means to cause relative approaching movement between the group of heddles and the selecting device whereby to place a space E in register with the corresponding selector and then a space F in register with the other selector.

4. A heddle-selecting and advancing mechanism to operate upon a series of independent heddles characterized by regular alternate variation of the members of the series, said mechanism comprising a rotatably mounted device consisting of an abutment and two selectors spaced from the abutment sufficiently to receive a single heddle and located at opposite sides of the abutment, one of said selectors coacting with one of said variations, and the other selector coacting with the other variation, said device also comprising a double-acting wedge located diametrically opposite the abutment and adapted to advance a selected heddle, and means to rotate said device alternately in opposite directions.

5. A heddle-selecting mechanism to operate upon a series of independent heddles characterized by regular alternate variation of the members of the series, said mechanism comprising a pivotally mounted device consisting of an abutment and two selectors spaced from the abutment sufficiently to receive a single heddle and located at opposite sides of the abutment, one of said selectors coacting with one of said variations, and the other selector coacting with the other variation, and means to turn said device alternately in opposite directions.

6. A pivotally supported heddle-selecting and advancing device comprising an abutment, two selectors spaced from the abutment sufficiently to receive a single heddle and located at opposite sides of the abutment, and a wedge-shaped heddle-advancing projection located diametrically opposite said abutment.

7. A pivotally supported heddle-selecting device comprising an abutment, and two

selectors spaced from the abutment sufficiently to receive a single heddle and located at opposite sides of the abutment.

8. In a mechanism for operating upon a series of heddles strung upon a heddle-supporting bar, the combination of heddle-selecting mechanism, means to press a group of heddles against said mechanism, and a reciprocatory presser arranged to engage the upper ends of heddles adjacent to said selecting mechanism to press downwardly any heddle which may be above its normal position.

9. A heddle-selecting mechanism to operate upon a compact series of steel heddles comprising means for supporting such a series of heddles, a selecting device pivoted upon an axis extending at one side of the series of heddles, said device comprising an abutment at one side of the axis of the device to be engaged by the foremost heddle of the series, two selectors on the same side of the axis of said device and spaced away from the abutment and toward the series of heddles sufficiently to provide space for the foremost heddle, said selectors being located at opposite sides of the abutment, a wedge-shaped heddle-advancing projection located diametrically opposite said abutment, and means for rotating said device through a complete revolution alternately in opposite directions.

10. A heddle-selecting mechanism to operate upon a compact series of steel heddles comprising means for supporting such a series of heddles, a selecting device pivoted upon an axis extending at one side of the series of heddles, said device comprising an abutment at one side of the axis of the device to be engaged by the foremost heddle of the series, two selectors on the same side of the axis of said device and spaced away from the abutment and toward the series of heddles sufficiently to provide space for the foremost heddle, said selectors being located at opposite sides of the abutment, and means for oscillating said selecting device to bring the selectors alternately into action.

11. In a heddle-selecting mechanism to operate upon a compact series of steel heddles, means for supporting such a series of heddles, a selecting device pivoted upon an axis extending at one side of the series of heddles, said device comprising an abutment at one side of the axis of the device to be engaged by the foremost heddle of the series, a selector on the same side of the axis of said device and spaced away from the abutment and toward the series of heddles sufficiently to provide space for the foremost heddle, and means for oscillating said selecting device.

12. A mechanism adapted to operate upon a compact series of steel heddles formed to provide a space between successive heddles,

said spaces extending entirely through the series of heddles, and heddle selecting means including a relatively thin element adapted to enter said spaces, and a wedge-shaped element following said thin element and adapted to spread apart the heddles between which the space is formed, said elements

being rigidly connected together diametrically opposite each other and pivoted upon an axis located exteriorly of and alongside 10 the series of heddles.

In testimony whereof, I have hereunto affixed my signature.

PRESTON W. CUMMINGS.
